UNITED STATES PATENT OFFICE.

EDWARD CLIFF, OF NEWARK, NEW JERSEY.

CAR-TRUCK.

SPECIFICATION forming part of Letters Patent No. 539,933, dated May 28, 1895.

Application filed May 7, 1894. Serial No. 510,298. (No model.)

To all whom it may concern:

Be it known that I, EDWARD CLIFF, of Newark, in the county of Essex, in the State of New Jersey, have invented new and useful 5 Improvements in Car-Trucks, of which the following, taken in connection with the accompanying drawings, is a full, clear, and exact description.

My invention relates to car trucks, particularly street car or motor trucks and the object is to provide an easier riding car and to prevent undue vibrations thereof.

To this end my invention consists in the combination with a stationary or lower frame 15 supported upon the running-gear, said frame having sections extending outwardly from the axle, of a movable or upper frame supported upon said truck, spiral springs located between the said upper and lower frames, a half- 20 elliptic spring located between each extended section of the said lower frame and the upper frame, the axle-boxes, pedestals or yokes in the lower frames, and springs between the said axle-boxes and yokes; and my invention consists in certain other combinations of parts 25 hereinafter described and specifically set forth in the claims.

In the drawings hereto annexed and forming a part of this specification, Figure 1 is a 30 side elevation of my improved truck. Fig. 2 is an enlarged side view of the pedestal and axle-box thereof. Fig. 3 is a top plan view of the axle-box, taken on line $x-x$ of Fig. 2; and Fig. 4 shows a modified arrangement of the 35 spiral springs on the pedestal and axle-box.

Referring specifically to the drawings, A represents the wheels; B, the axle-boxes; C, the upper or movable frame, and D the lower, or what is sometimes termed the stationary 40 frame. The lower frame may have its sides in one piece but they are preferably made in three parts, that is, the end portions, D'', are connected together by side-beams, D', bolted or riveted thereto, the side-beams, D', being connected together by transversely extending bars, d, d, bolted or riveted to the side beams. The pedestal or yoke for each 45 axle-box is preferably integral with the extended end portions of the lower frame.

D'' are the outwardly extending sections or parts of the sides of the lower frame which form the bed of the extended spring base,

said sections extending outward from the pedestal some distance. The end portions, D'' may be made of malleable or steel castings 55 connected together by steel bars, D', lying and bolted in sockets.

The movable or upper frame upon which the car-body rests is preferably rectangular in form and longer than the lower frame. 60 Spring plates or sockets, c, c, are secured to the lower side of the upper frame above the pedestals on the lower frame and corresponding spring sockets, c', c', are in the upper side of the pedestals to receive spiral springs, 65 E, extending between the two frames of the truck. In Figs. 1 and 4 I show a single spiral spring above each pedestal, or two spiral springs one within the other, but in Figs. 2 and 3 a pair of spiral springs are shown side 70 by side on each pedestal between the latter and the upper frame.

On the lower side of each pedestal are spring sockets, e, e, and corresponding spring sockets, e', e', formed on the sides of each axle-box beneath the sockets, e, e, to receive the ends of spiral springs, F, F, between the said parts. Extending vertically through the center of the springs, F, F, and through the pedestal or yoke of the frame are bolts or spring-posts, f, f. 80

F' is a detachable retaining piece extending horizontally between the sides of a yoke and below the axle-box which can be detached for the purpose of removing the said box from the yoke or frame. 85

b, b are spring-hangers depending from the upper frame of the truck to receive one end of each of the end semi-elliptic springs G. These springs are located between the extensions of the lower and upper frames and the 90 lower parts of the elliptic springs are preferably used. Each of said springs is held at its center in a frame, g, having a projection on its lower side, which enters and lies in a socket, g', on the end of an extension, D'' so that the 95 frame, g, may rock slightly therein. A bolt, g'' extends through the said projection and washers on each side of the extension, D'' to hold the parts securely in place. The inner ends of these elliptic springs are coupled to 100 the lower frame by links and the outer ends are coupled or pivoted to the hangers, b, b, on the upper frame.

Extending between the inner ends of the

yokes above the side bars, D', are the upper parts of semi-elliptic springs H. Said springs are shackled at their ends to the yokes and the central parts are held in frames, h, having projections on their upper sides which lie in sockets, h', secured to the under side of the middle of the upper frame C.

The upper frame, C, may be formed by the bottom of the car-body if desired, and the 10 spring-hangers and sockets secured thereto.

Any matters shown or described herein relative to the truck-frames and springs are not dedicated to the public, but form the subject matter of another application filed September 15, 1893, Serial No. 485,121.

Having described my invention, what I claim as new, and desire to secure by Letters Patent, is—

1. In a car-truck, the combination with the 20 lower frame supported upon the running gear, said frame having end sections extending outwardly from the yokes and integral with the said yokes, bars extending between the said end sections and secured in sockets 25 therein, an upper frame mounted on said truck, spiral springs between the two frames, a half-elliptic spring between the extended sections and the upper frame, one end of said spring being linked to the lower frame, and 30 its opposite end being linked to the upper frame, and semi-elliptic springs between the yokes on each side between the two frames as set forth.

2. In a car-truck, the combination with the 35 lower frame supported upon the running gear, said frame having end sections extending outwardly from the yokes and integral with the said yokes, bars extending between the said end sections and secured in sockets 40 therein, an upper frame mounted on said truck, spiral springs between the two frames, a half-elliptic spring between the extended sections and the upper frame, one end of said spring being linked to the lower frame, and 45 its opposite end being linked to the upper frame, and the upper part of an elliptic spring shackled to the yokes on each side of the

truck, and having its central bearing lying in a socket secured to the upper frame, as set forth.

3. In a car truck, the combination of the upper and lower frames mounted upon the running gear, lower halves of elliptic springs between the end portions of said frames and having their outer ends shackled to the upper frame and their inner ends shackled to the lower frame, central bearings for said springs, and sockets in the ends of the lower frame to receive the bearings, as set forth.

4. The combination with an axle-box, a pedestal having its vertical sides remote from said axle-box, and an upper frame of a truck, of a support for a spiral spring on each side of the axle-box, spiral springs between the said supports and the upper horizontal portion of the pedestal, and between the said vertical sides and the sides of the axle-box, bolts passing through said supports and held stationary in the pedestal and a spiral spring between the upper side of the pedestal and the upper frame.

5. The combination with an axle-box, a pedestal having its vertical sides remote from said axle-box, and an upper frame of a truck, of a socket for a spiral spring on each side of and integral with the axle-box, sockets in the lower side of the pedestal directly above the first mentioned sockets, spiral springs extending between said sockets, bolts passing vertically through said springs and held securely in position and stationary in the pedestal, spring sockets in the upper side of the pedestal directly above the other sockets, spring sockets secured to the said upper frame, and spiral springs extending between the pedestal and said upper frame and lying in the sockets, as set forth.

In testimony whereof I have hereunto signed my name.

EDWARD CLIFF. [L. S.]
